(57) **CLAIM**

The ornamental design for an irrigation device, as shown and described.

DESCRIPTION

FIG. 1 is a front perspective view of an irrigation device showing my new design;

FIG. 2 is a bottom rear perspective view thereof;

FIG. 3 is a front elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear elevational view thereof;

FIG. 9 is a front perspective view of the irrigation device of FIG. 1 shown in a closed condition;

FIG. 10 is a close-up view of section 10 from FIG. 2;

FIG. 11 shows the irrigation device of FIG. 9 in a use condition;

FIG. 12 is a front perspective view of an alternate embodiment of an irrigation device showing my new design;

FIG. 13 is a bottom rear perspective view thereof;

FIG. 14 is a front elevational view thereof;

FIG. 15 is a left side elevational view thereof;

FIG. 16 is a right side elevational view thereof;

FIG. 17 is a top plan view thereof;

FIG. 18 is a bottom plan view thereof;

FIG. 19 is a rear elevational view thereof; and,

FIG. 20 is a close-up view of section 20 from FIG. 13.

The broken lines represent portions of the irrigation device and form no part of the claimed design.

1 Claim, 9 Drawing Sheets
